UNITED STATES PATENT OFFICE

DONALD E. WILLARD, OF DANVILLE, ILLINOIS

DESIGN FOR A VEHICLE WHEEL

Application filed August 8, 1932. Serial No. 44,555. Term of patent 14 years.

To all whom it may concern:

Be it known that I, DONALD E. WILLARD, a citizen of the United States, residing at Danville, in the county of Vermilion and State of Illinois, have invented a new, original, and ornamental Design for Vehicle Wheel, of which the following is a specification, reference being had to the accompanying drawing, forming part thereof.

Fig. 1 is a front elevation of a vehicle wheel, showing my new design.

Fig. 2 is a sectional elevation taken along the line 2—2 in Fig. 1, looking in the direction of the arrows.

I claim:

The ornamental design for a vehicle wheel as shown.

DONALD E. WILLARD.
